Primary Examiner—Holly H Baynham*Assistant Examiner*—Cynthia M Chin(74) *Attorney, Agent, or Firm*—Ohlandt, Greeley, Ruggiero & Perle, L.L.P.(57) **CLAIM**

The ornamental design for a cup lid, as shown and described.

DESCRIPTION

FIG. 1 is a front, top perspective view of the lid according to the present disclosure;

FIG. 2 is a front elevation view of the lid of FIG. 1;

FIG. 3 is a rear elevation view of the lid of FIG. 1;

FIG. 4 is a top plan view of the lid of FIG. 1;

FIG. 5 is a bottom plan view of the lid of FIG. 1;

FIG. 6 is a left side elevation view of the lid of FIG. 1; and,

FIG. 7 is a right side elevation view of the lid of FIG. 1.

The broken lines in the drawings illustrating environmental structure or boundaries is for illustrative purposes only and forms no part of the claimed design.
